UNITED STATES PATENT OFFICE.

ALEXANDER CUNNING, OF PORT HURON, MICHIGAN.

PONTOON FOR RAISING SUNKEN VESSELS.

1,292,718.

Specification of Letters Patent. Patented Jan. 28, 1919.

Application filed August 9, 1918. Serial No. 249,101.

To all whom it may concern:

Be it known that I, ALEXANDER CUNNING, a citizen of the United States of America, residing at Port Huron, in the country of St.

5 Clair and State of Michigan, have invented certain new and useful Improvements in Pontoons for Raising Sunken Vessels, of which the following is a specification, reference being had to the accompanying drawings.

10 An object of my invention is to provide novel pontoons for raising sunken or stranded vessels, the pontoons serving as lighters for salvage work and as quarters and work-shops for wrecking crews.

15 Another object of my invention is to provide novel salvage pontoons that may be safely used for raising sunken vessels on an even keel, without any danger of the pontoons colliding or capsizing, and provision is made for expeditiously handling the hoisting chains or cables of the pontoons.

20 A further object of my invention is to provide wrecking vessels that may be used for various kinds of salvage work, the vessels being primarily designed to be used in pairs so that the vessels may coöperate in lifting loads that otherwise could not be handled by a single vessel.

25 30 The above are a few of the objects gained by the novel construction which will be hereinafter described and then claimed, and reference will now be had to the drawings, wherein—

35 Figure 1 is a plant of a pontoon, partly broken away;

Fig. 2 is a diagrammatic longitudinal sectional view of the same;

Fig. 3 is an enlarged cross sectional view 40 of a portion of a pontoon, taken about midship;

Fig. 4 is a plan of a portion of the pontoon, showing a diver's way, and

Fig. 5 is an end view of a set or pair of 45 pontoons in position for raising a sunken vessel.

Each pontoon is constructed of strong and durable material, preferably from structural steel including girders, beams, columns, side and bottom plates, web plates, hatchways, trusses and braces, all fabricated to form a rigid hull that is substantially rectangular in cross section, the hull having a flat bottom 1, parallel side walls 2, an arched

50 55 upper deck 3, intermediate decks 4 and 5 and undercut ends 6 that may serve either as the

stern or bow of the pontoon, it being preferable to use the pontoons simply for work purposes irrespective of any propulsion means whatsoever.

60 The upper deck of the pontoon is provided with a plurality of hatchways 7 and these hatchways communicate with compartments 9 between the decks 3, 4 and 5, thus permitting of the pontoon being used 65 as a lighter or for storage purposes at a dock. Along the side of the hatchways 7 are rails 10, constituting a track for a traveling crane or derrick 11, and this derrick may have its own source of power, as shown, 70 or depend on a boiler 12 located in a boiler and pump room 13 at one side of the pontoon. The same side of the pontoon may have coal bunkers 14 and such other compartments which must be contiguous to a 75 boiler and engine room.

75 Between the lower deck 5 and the bottom of the hull are compartments 15 and somewhat similar compartments 16 may be constructed at the sides of the pontoon, said compartments being used to increase or decrease the buoyancy of the pontoon. For instance, all of the compartments may be constructed as air tight compartments that will, under ordinary circumstances, positively prevent the pontoon from sinking. It is also possible to use the compartments for water which may be admitted to the compartments by sea valves, to cause the pontoon to sink a prescribed distance relative to 90 the surface of the water in which the pontoon floats.

95 By providing suitable pumps about the pontoon, the water compartments can be emptied and thus cause the buoyancy of the pontoon to assist in a raising operation. This is particularly advantageous after pontoons have been attached to a sunken vessel, as the low position of the pontoon in the water will facilitate diver operations and serve as a ballast particularly in a rough sea. Then, after all preparations have been made for raising a load, the compartments may be pumped out and thus cause the pontoons to perform the initial raising operations, independent of any hoisting engines or other mechanism. It is with such ends in view that I do not care to confine myself to the specific use of the compartments 15 and 16.

100 105 110 One side of each pontoon has a plurality of angularly disposed chain or cable ways 17

and 18, said chain ways being in the form of tubes or pipes having the upper ends thereof terminating at socket members 19 in the deck 3 and adjacent the hoists, steam 5 winches, or chain winding devices 20, said devices being of a conventional form ordinarily employed for raising or pulling in anchor chains.

The lower ends of the chainways 18 terminate in socket members 21 in the bottom 1 of the pontoon, and the lower ends of the chainways 17 terminate in socket members 22, carried by the inner walls 23 of diver ways 24, said diver ways extending from the 15 deck 3 to the bottom 1 of the pontoon, with the inner wall 23 provided with ladders or hand grips 25. It is necessary that the chainways 17 and 18 extend through some compartments of the pontoon and the arrangement of the chainways necessitates the chainways 17 being at a greater angle than the chainways 18, and this is in order that certain chains 26 may extend from the bottom of the pontoon and under a sunken vessel 27, while other chains 28 extend from the confronting sides of a pair of pontoons and are attached to the sides or gunwales of the sunken vessel 27, as best shown in Fig. 5..

In order that a pair of pontoons may 30 safely coöperate in raising a sunken vessel, the sides of the pontoons having the diver and chainways are provided with a plurality of extensible booms 29 that may be extended by power or manually, said booms being in 35 opposed relation with the confronting ends thereof connected by ball and socket joints 30 or any conventional form of universal joint which will permit of the pontoons freely floating in parallelism and spaced relation, without any danger of collision or a 40 separation which would materially interfere with the raising of the sunken vessel.

With the chainways and chains properly distributed throughout the length of the 45 pontoons and the hoisting engines individually automatically or collectively controlled, similar to towing engines, it is possible to raise the sunken vessel on an even keel, and of course the initial movement of 50 the vessel may be greatly facilitated by removing a portion or all of the contents thereof, and by using the buoyancy of the pontoon prior to the hoisting engines.

Copies of this patent may be obtained for five cents each, by addressing the "Commissioner of Patents, Washington, D. C."

Each pontoon is equipped with fore and aft anchors 31 together with the necessary 55 mechanism for raising and lowering the said anchors. After locating a sunken vessel or wreck, it is therefore possible to anchor the pontoon in proper position for raising or work about the sunken vessel, and as salvage 60 operations ordinarily require some time, each pontoon is provided with quarters for the officers and crew, machine shop, and all appurtenances to expedite operations about a sunken vessel. 65

It is thought that the use of the pontoons will be apparent without further description, and while in the drawings there is illustrated a preferred embodiment of my invention, it is to be understood that the structural elements are susceptible to such variations and modifications as fall within the scope of the appended claims. 70

What I claim is:—

1. A pontoon having a deck and side diver 75 ways with the outer sides thereof open to the atmosphere and water and extending throughout the depth of the pontoon, a ladder in each diver way, chainways extending from said deck to said diver ways and to the 80 bottom of said pontoon and having the ends thereof open with those chainways having the ends thereof opening at the bottom of said pontoon between those chainways opening into the diver ways, hoisting chains extending through said chainways, and means on said deck adapted for raising and lowering said chains. 85

2. The combination of a pair of pontoons having the confronting sides thereof provided with diver ways having the outer sides thereof open to the atmosphere and water, booms carried by the confronting sides of said pontoons and having ends thereof loosely connected to maintain said pontoons 90 in spaced relation, chainways at the confronting sides of said pontoons, chains extending through said chainways, and means on said pontoons adapted for raising and lowering said chains. 95

In testimony whereof I affix my signature in the presence of two witnesses.

ALEXANDER CUNNING.
